LAMP FOR HELMETS OR THE LIKE

Anthony M. Carlini, 24340 Cherry Hill Road,
Dearborn, Mich. 48124

Filed Sept. 20, 1971, Ser. No. 182,301

Term of patent 14 years

Int. Cl. D26—02

U.S. Cl. D48—24 A

FIG-1

FIG-2

FIG-3

FIG-4

FIG-5

FIG-6

FIG. 1 is a perspective view of a lamp for helmets or the like, showing my new design;

FIG. 2 is an enlarged side elevational view thereof;

FIG. 3 is an enlarged top plan view thereof;

FIG. 4 is an enlarged rear elevational view thereof;

FIG. 5 is an enlarged front elevational view thereof;

and

FIG. 6 is an enlarged bottom plan view thereof.

The helmet is shown in broken lines in FIGS. 1 and 2 for illustrative purposes only.

I claim:

The ornamental design for a lamp for helmets or the like, as shown and described.
